UNITED STATES PATENT OFFICE.

MENOTTI NANNI, OF CHICAGO, ILLINOIS.

SAFE.

1,410,027.

Specification of Letters Patent. Patented Mar. 21, 1922.

Application filed April 24, 1919. Serial No. 292,318.

To all whom it may concern:

Be it known that I, MENOTTI NANNI, a subject of the King of Italy, and a resident of the city of Chicago, county of Cook, and State of Illinois, have invented certain new and useful Improvements in Safes, of which the following is a specification.

My invention relates to improvements in safes, and has for its object the provision of an improved construction of this character which may be readily transported; which is so constructed as to prevent opening the same through the force of explosions, and the combination of which is protected from destruction or injury from the outside thereof.

Other objects will appear hereinafter.

The invention consists in the combinations and arrangements of parts hereinafter described and claimed.

The invention will be best understood by reference to the accompanying drawings forming a part of this specification, and in which,

Fig. 1, is a perspective view of a safe embodying the invention, shown open,

Fig. 2, an enlarged section taken on the plane indicated by the line 2—2 on Fig. 1,

Fig. 3, a front view of the safe,

Fig. 4, a horizontal section of the same, and

Fig. 5, an enlarged vertical section of the safe.

The preferred form of construction, as illustrated in the drawings, comprises a safe made up of detachable sections, the top and bottom sections 6 and 7, respectively, being channeled at their edges to receive the upper and lower edges of the side sections 8 and the back section 9, the front of the safe being in the form of a removable hinged door 10. The bottom section 7 is provided with suitable removable feet or legs 7' for supporting the same. All of the sections are made hollow and provided with an outer chamber 11 filled with mineral wool, or the like, for fire protection, and an inner open air chamber 12 having perforations 13 leading through the inner wall thereof, into the interior of the safe, to permit of the free passage of air. The various sections are provided with securing lugs or ears 14 located on the interior of the safe and secured in place by means of screws 15 taking into suitable posts 16, as shown, and whereby the top,

bottom, side and rear wall sections of the safe may be detachably secured in place, but can only be detached when the safe door is open, so that access may be had to the heads of the screws 15. In this way ample security is afforded against unauthorized opening of the safe, but at the same time, the safe, when opened, may be readily taken apart for convenience in transportation.

Hollow blow-out plugs 17 are secured in the outer wall's of the safe sections leading into the air chambers thereof, the outer walls of said blow-out plugs being sufficiently weak and fragile to cause the same to fracture or break upon the generation of excessive pressure within the safe, thus permitting of the escape of such pressure. In this way, in case an attempt is made to "blow" the safe, and open the same by the use of explosives, the internal pressure generated by the explosive will serve to fracture the various blow-out plugs and thus dissipate the pressure without blowing open the door of the safe.

The door of the safe is provided with the usual locking bolt or bolts operated by the handle 18, said bolts being in turn controlled in the usual manner by the usual disc 19 of the usual combination lock. This disc 19, instead of being provided with the usual handle for manipulating the same, is set or mounted within a casing 20 imbedded within the wall of the door 10, said disc being mounted flush with the outer surface of the door so as to protect the same and prevent ready injury thereto. The disc is provided with a key socket 20, positioned centrally therein as shown, and whereby a key may be inserted therein for turning the same but no material force may be applied to the disc or the combination through said key. This arrangement prevents the effective application of force from the outside to the combination of the safe, thus further protecting the same from unauthorized tampering.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A safe having hollow walls comprising inner and outer chambers, the walls of said inner chambers being provided with openings for the circulation of air toward the interior of the safe; blow-out plugs mounted in openings extending through the outer chambers and terminating within said inner chambers, permitting escape of compressed air and gases from said inner chambers or from the interior of the safe to the exterior thereof; and protective filling material within said outer chambers, substantially as described.
  2. A safe having detachable hollow walls comprising inner and outer chambers, said inner chambers being in open communication with the interior of the safe; blow-out plugs mounted in openings extending through the outer chambers and terminating within said inner chambers, said plugs having fragile tops permitting escape of gases under excessive pressure from said inner chambers or from the interior of the safe to the exterior thereof; and means accessible only from the interior of the safe for fastening said inner and outer chambers and said walls together, substantially as described.
  3. A safe having compound hollow walls comprising inner and outer chambers, the in-
- ward walls of said inner chambers being provided with a plurality of rows of openings for the circulation of air toward the interior of the safe; and blow-out plugs mounted in openings extending through both walls of the outer chambers, said plugs terminating within said inner chambers and being provided with fragile tops permitting escape of air and gases under excessive pressure from the interior of the safe or from said inner chambers to the exterior of the safe, substantially as described.
4. A safe having hollow walls forming superposed air chambers, there being a multitude of openings in the walls between said air chambers and the interior of said safe; blow-out plugs mounted in the side walls of the outer air chambers, permitting the escape of compressed gas and air from said safe and inner air chambers, upon generation of an excessive pressure within said safe; and threaded members engaging the three walls of said superposed chambers for holding said walls together, substantially as described.

In testimony whereof I have signed my name to this specification in the presence of two subscribing witnesses.

MENOTTI NANNI.
